UNITED STATES PATENT OFFICE.

WINFIELD S. LIVENGOOD, OF KANSAS CITY, MISSOURI, ASSIGNOR TO SMITH & SONS MFG. CO., OF KANSAS CITY, MISSOURI.

ROAD-GRADER.

No. 847,793.

Specification of Letters Patent.

Patented March 19, 1907.

Application filed June 18, 1904. Serial No. 213,066.

To all whom it may concern:

Be it known that I, WINFIELD S. LIVENGOOD, a citizen of the United States, residing at Kansas City, in the county of Jackson and State of Missouri, have invented certain new and useful Improvements in Road-Graders, of which the following is a specification.

My invention relates to wheeled road scrapers or graders; and the object of my invention is to provide a scraper of this kind with easily-operated devices for changing the angle of the scraper-blade, raising and lowering either end thereof, shifting the same in a direction parallel to its length, and raising or lowering the forward end of the scraper-beam, all of which adjustments may be effected by the operator while standing upon a platform at the rear of the machine, as herein-after described, and shown in the accompanying drawings.

In the said drawings, Figure 1 is a right-side elevation of a road scraper or grader constructed in accordance with my invention, a portion of the tongue, its spring, and of the hind wheels being broken away. Fig. 2 is a transverse sectional view taken on line II II of Fig. 1, omitting the tool-box and seat. Fig. 3 is a central vertical section of the front portion of the frame, including a portion of the tongue or pole. Fig. 4 is a rear elevation of the machine, omitting the parts which lie in front of line II II on Fig. 1. Fig. 5 is a plan view of the hind axle and the operator's platform, said axle being partly broken away and partly in horizontal section and a different position of the platform being shown in dotted lines. Fig. 6 is a plan view of the rear portion of the machine, omitting the scraper-blade and the connected parts. Fig. 7 is a detached plan view of the parts which are omitted in Fig. 6, the front portion of the frame being indicated by dotted lines. Fig. 8 is a rear elevation of the means for shifting the scraper-blade transversely, parallel to its own length, the lower bearing of the vertical shaft being shown in section. Fig. 9 is a sectional plan view taken on line IX IX of Fig. 8. Fig. 10 is a detail section, enlarged, taken on line X X of Fig. 7, omitting the bar 33. Fig. 11 is an enlarged longitudinal section of the universal joint. Fig. 12 is a transverse sectional view taken on line XII XII of Fig. 3; and Fig. 13 is a longitudinal section of the rear axle, sliding bolster, and platform, taken on line XIII XIII of Fig. 4.

Referring to Figs. 1 and 4, the frame of the vehicle, supported by the four-wheel running-gear, consists of two longitudinal beams 11, preferably of channel-section, as shown. The rear ends of said beams are supported by an arch 2, the ends of which are bolted to lugs 3, formed on the ends of a channel-bar 4, hereinafter termed the "sliding bolster," as it is mounted slidably upon the rear axle 5 for the purpose hereinafter stated. Said sliding bolster extends the full width of the frame to provide a wide bearing-surface for axle 5, so the latter will not bend beneath the weight of the machine when the bolster is shifted longitudinally on the axle. The front ends of beams 11 are supported as follows: An arched bolster 6, Fig. 12, is mounted on the front axle 7 by means of clips 8, and two outwardly and upwardly inclined braces 9 are supported by said arch 6. As shown in Figs. 3 and 12, these braces 9 support a transverse beam 10, on which rest the forward ends of the side beams 1. A king-bolt 12 extends from cross-beam 10 down through the arched bolster 6. Rigidly secured to the bottom of said bolster is a forwardly-projecting lug 13, to which the bifurcated end of the tongue 14 is connected by a bolt 15. The weight of the tongue is partially supported by a chain 16, into which is connected a heavy spring 17. The clevis 18 on the tongue is provided for connection of a doubletree. (Not shown.) Two braces 19 extend from the lower ends of braces 9 to the inner sides of channel-beams 1, to which they are connected at 20, Fig. 1. A cross-bar 21, supporting seat-spring 22, is bolted to the top flanges of beams 1.

23 is a tool-box.

The scraper-plate 24 is supported as follows, reference being had to Figs. 1 and 6: Two rock-shafts 25 and 26 are supported by forward bearing-stands 27 and rearward bearing-stands 28, bolted to the channel-beams 1. Crank-arms 29 and 30 are bent on the forward ends of said respective shafts, and pivotally connected to said crank-arms are two depending rods 31 and 32, the lower

ends of which are pivotally connected to a sway-bar 33, as most clearly shown in Fig. 2. Said rods are connected to the said cranks and to the bar 33 in such a manner that they are free to swing in any direction, forwardly and backwardly, as well as laterally. Bolted or riveted to the sway-bar 33 by clamps 34 are the rearward ends of two forwardly-extending beams 35, which converge and are secured to a shank 36. The end of the shank is provided with a vertical opening of sufficient size to loosely receive the king-bolt 12, which extends therethrough, Fig. 3. Thus the shank 36 is free to be turned laterally for the purpose explained hereinafter.

As shown, the beams 35 are arched at 96 to permit the front wheels to pass thereunder when the tongue is turned at one oblique angle.

Supported by the sway-bar 33 and beams 35 is a ring 37. This is effected by the clamps 34 and clamps 38. A cross-brace 40 may be employed, connecting the beams 35 and being secured to the ring 37 by means of a knee 41 and bolts 42.

The ring 37 is provided with a peripheral flange 37^a, (see Fig. 10,) which supports an independent rotatable geared ring 43. At the rear this ring is held seated by a plate 44, bolted to the inner ring 37, bent upwardly and secured to the sway-bar 33 at 45.

A heavy horseshoe-shaped bar 46 (shown in Figs. 1, 2, and 7) is supported by the forward portion of the geared ring 43. As shown, this is effected by means of bolts 47. The middle portion of the bar 46 conforms to the curve of the ring, and from this middle portion it extends rearwardly, then downwardly, forming two shanks 48. Hinges or knees 49, secured to the rear face of the scraper-plate 24, are pivotally connected to the ends of said shanks by means of bolts or pins 50. The scraper-plate is further connected to the shanks 48 by means of arms 51, pivotally connected to the scraper at 52 and to the shanks by bolts 53. Said arms are provided with a plurality of holes, as shown, in any one of which the bolts 53 may be placed, whereby the pitch of the scraper-plate is adjustable to different angles when so desired.

It will thus be understood that the scraper-plate is supported through the intermediary of the parts described, which parts include the aforesaid rock-shafts 25 and 26.

Fixed upon the rear ends of these shafts are two gear-wheels 54 55, Figs. 4 and 6, respectively, engaged by worms 56 and 57, the hubs of which are rigidly secured to the hubs of two hand-wheels 58 and 59. Said worms and hand-wheels are loosely mounted on a shaft 60, which is supported by lugs 61 of the bearing-stands 28. Thus the hand-wheels 58 and 59 may be turned independently, and

thereby the ends of the scraper-plate 24 may be separately raised or lowered by the operator.

As shown in Figs. 2 and 6, the rock-shafts 25 and 26 are provided with tension-springs 62 63, the purpose of which is to exert a lifting effect upon the arms 29 30 and rods 31 32, thus relieving the worm-gears of a part of the friction caused by the weight of the parts supported by the arms 29 30. The lower ends of the said springs are connected to eye-bolts 63, and the springs are secured to cams 64 or equivalent devices 64, fixed upon the opposite respective shafts in such a manner as to tend to lift the arms 29 30 for the purpose named.

In Fig. 2, 65 are two braces which extend from the geared ring 43 to the scraper-plate, they being connected, preferably, to the knees or hinges 49, as shown, and may consist of a single bar of metal, as shown.

I provide means for raising or lowering the shank 36 on the scraper-beams 35 for the purpose of altering the pitch of the scraper without handling the adjusters 51. As shown in Fig. 3, a chain 66 is connected to the shank 36 adjacent to the king-bolt, 90 passes over two pulleys 67 68, Fig. 2, and connects to a rod 69, Fig. 6, to the opposite end of which a winding-chain 70 is connected. This chain passes onto a small drum 71, which may be the elongated hub of a ratchet-wheel 72. 73 is the pawl, having the usual function. On the shaft of the drum 71 is a hand-wheel 74, by turning which in one direction the shank 36 may be raised, thus changing the angle of the beams 35, and by throwing off the pawl 73 and permitting the hand-wheel to turn the beams will drop of their own weight until the shank rests upon the bolster 6.

Returning to the geared wheel 43, the means for rotating it will now be described. Engaging the said ring at one side, preferably the right, is a worm 75, the shaft of which is journaled in two bearings 76 and 77.

The rear bearing 76 is secured to the sway-bar 33 by a bolt 78. The front bearing 77 is supported by a bracket 79, bolted to one of the beams 35. Said worm-shaft 80, Fig. 3, is connected by a universal joint 81 to a shaft 82 in such a manner that the shaft 82 can slide longitudinally within the sleeve 83, but will rotate the same by means of a pin 84, tightly fixed therein and projecting through two slots 85, cut in the said sleeve. Shaft 82 extends back and is connected by a second universal joint 86 to a shaft 87, which is set at such an angle that a hand-wheel 88, fixed thereon, is at convenient height for the operator. By turning this wheel 88 the geared ring 43 is rotated, and thereby the shanks 48 and the scraper-plate 24, and the latter is

thus adjusted to the proper angle for use, which is well known and requires no description.

As hereinafter described, the rearward ends of the longitudinal frame-beams 11 are supported by an arch 2 and a sliding bolster 4. This bolster is shown in transverse section in Fig. 13. A stationary rack-bar 89, Fig. 5, is held beneath the rear axle, preferably with bolts 90, passing through lugs 91 and 92. The forwardly-directed teeth of the rack are engaged by a pinion 93, fixed upon the lower end of a vertical shaft 94. The upper bearing of said shaft is provided by a bearing 95. (Shown in Figs. 4 and 6.) This bar is partly supported by shaft 60, and its rear end is secured to the top of arch 2. The lower bearing of shaft 94 is provided by a block 96, (shown in section in Fig. 8,) bolted to the front of the sliding bolster 4. A hand-wheel 98 is fixed upon the upper end of shaft 94, and by turning the same the sliding bolster 4 and the arch 2 may be moved bodily to the right or the left, carrying with them the scraper-plate 24 and all its supporting parts, hereinbefore described.

The operator's platform 99 is attached to the sliding bolster 4 with bars 100 and is provided with braces 101, which are hung from the arch 2. The bars 100 extend forwardly and upwardly, forming braces 102. These braces are secured to the lower flanges of the channel-beams 11.

As indicated in Fig. 5, the platform 99 moves laterally with the pinion 93 and the bolster 4. By turning hand-wheel 98 the operator can shift the scraper-plate laterally a few feet either to right or left. The advantage of this movement will be appreciated by any one who has occasion to manufacture or use a grader of this type. The rack 89 may be made longer than indicated in Fig. 5 and the sliding part 4 shortened, if it be desired to increase the range of the scraper's transverse movement.

Figs. 8 and 9 illustrate in detail my device for holding or locking the pinion 93 at any point in its travel for the purpose of preventing unintentional side motion of the frame. 50 103 is a vertically slideable and rotatable rod, the lower end of which forms a dog that may be let down between any two teeth of the pinion 93. This rod is pressed downwardly by an expansion-spring 104. The upper end of 55 the rod is bent substantially a right angle, forming a handle 105, which rests upon an arc-shaped and inclined cam 106, rigidly secured to plate 95 with a bolt 107. The operation is obvious and requires no description.

In addition to the various adjustments described I have provided means for enabling the operator to shift the scraper-plate longitudinally of its length without moving the

framework—i. e., the channel-beams 11. As shown in Fig. 6, a shaft 109, having bearings 110 and 111, has a hand-wheel 112 mounted on its rear end and a worm 113 on its forward end. Worm 113 engages a gear-wheel 114 on a vertical shaft 115, on which is fixed a rearwardly-extending crank 116, to which is pivotally connected a rod 117. This rod is broken away in Fig. 6; but in Figs. 2 and 7 it is shown connected to the sway-bar 33 by a hinge-joint 118. It is thus evident that the sway-bar may be moved in the direction of its length suspended by rods 31 32 by turning hand-wheel 112. Braces 119 extend from the inner sides of bearing-stands 27 back to the channel-beams 1, to which they are secured.

The forward bearings 27 of rock-shafts 25 and 26 may be constructed integral with a cross-bar 27^a, (shown in Fig. 2,) the same being bolted against the inner sides of beams 1. 85 With bolts 120. The upper ends of the bearings 27 may be connected by a brace 121. (Shown in Figs. 2 and 6.)

A recapitulation of the operations of the different hand-wheels would be briefly as follows: The pitch of the scraper is adjusted by hand-wheel 74. The transverse movements of the scraper are effected by hand-wheel 98 or hand-wheel 112. The former shifts the entire frame of the machine; but the latter shifts only the parts directly supporting the scraper. The elevation and lowering of the ends of the scraper are accomplished by hand-wheels 58 and 59, and the angle at which the scraper is carried without reference to its elevation is adjusted by hand-wheel 88. All of these hand-wheels are within easy reach of an operator standing on the rear platform, and as nearly all the movements are accomplished through the instrumentality of worm-gearing the several parts will remain in the position placed without the employment of ratchet-wheels and pawls, which must be released before the hand-wheels can be turned in a certain direction; and consequently are a source of annoyance to the operator.

Springs 62 relieve the operator of the most difficult portion of the work by assisting in elevating the scraper-plate and its carrying mechanism.

Having now fully described my invention, what I claim as new, and desire to secure by Letters Patent, is—

1. In a wheeled grader, a scraper supported by two depending shanks, a horizontally-disposed gear-wheel supporting said shanks, a worm engaging the gear-wheel, and means for rotating said worm; substantially as described.

2. In a wheeled grader, a pair of rearwardly-diverging scraper-beams, means for raising and lowering their forward ends, a

- ring secured to their rearward ends, a geared ring rotatably mounted on said ring, self-locking means for operating said geared ring, two depending shanks supported by the 5 geared ring, a scraper secured to the shanks, means for supporting the inner ring and also the ends of said beams, and means for laterally shifting the scraper, substantially as described.
3. In a wheeled grader, a pair of rearwardly-diverging scraper-beams connected at their forward ends to a shank, said shank being vertically movable, a chain connected to said shank and extending upwardly and 15 rearwardly, and a windlass for lifting the shank by means of the chain; substantially as described.
4. In a wheeled grader provided at its rear portion with a platform, a pair of rearwardly-extending scraper-beams united at their forward ends, a cable for adjusting said ends vertically, and a windlass for adjusting the cable, said windlass being located near the platform so that it may be operated therefrom. 25
5. In a wheeled grader, a suitably-supported scraper, a large gear-wheel suitably connected to said scraper, a small gear-wheel intermeshing with the large wheel, means for 30 raising and lowering the scraper, a shaft upon which the small gear is fixed, a telescopic shaft flexibly connected to the small gear-shaft, and means for operating the telescopic shaft.
6. In a wheeled grader, provided at its rear portion with a platform, a suitably-supported scraper, a large gear-wheel suitably connected to said scraper, a small gear-wheel intermeshing with the large wheel, means for 35 adjusting the scraper longitudinally, a shaft upon which the small gear is fixed, a telescopic shaft flexibly connected to the small gear-shaft, and an operating-shaft flexibly connected at its forward end to said telescopic shaft and terminating at its rear end near the platform.
7. In a wheeled grader, a transverse sway-bar, a scraper indirectly supported thereby, a shaft having a crank at its lower portion, a 40 rod pivotally connected at its ends to the sway-bar and the crank, worm-gearing for operating the shaft, and means for operating said gearing.
8. In a wheeled grader provided at its rear portion with a platform, a transverse sway-bar, a scraper indirectly supported thereby, a shaft having a crank at its lower portion, a rod pivotally connected at its ends to the sway-bar and the crank a gear-wheel fixed 45 to the crank-shaft, a worm meshing therewith, a shaft fixed to said worm and extending rearwardly to a point near the platform, and means for operating said shaft.
9. In a wheeled grader, a pair of shanks, a 50 scraper, knees carried by said scraper and pivoted to the shanks, arms pivotally secured to said scraper and provided with a plurality of holes, and pins adapted to extend through holes in the shanks and any of the holes in the arms, whereby the pitch of 55 the scraper may be varied.
10. In a wheeled grader, the combination of a transverse bar, means for adjustably supporting the same, a scraper indirectly supported by said bar, a shaft provided with 60 a crank, a rod 117 connected to the bar and the crank, a gear-wheel fixed to the crank-shaft, a worm intermeshing with said gear-wheel, and means for operating said worm.
11. In a four-wheeled grader, the combination, with a rear axle, of a slideable bolster mounted thereon and extending the full width of the grader-frame, an arch mounted on said bolster, a longitudinal frame, rearwardly supported by said arch, a rack rigidly secured to said axle, parallel thereto, a vertical shaft carried by said arch and bolster, a pinion thereon, engaging the rack, and a hand-wheel on said shaft, a vertically-slideable and rotatable rod adapted to lock the 75 pinion, and means for normally holding said rod in engagement with the pinion; substantially as, and for the purpose, described.
12. In a wheeled grader, the combination of a transverse bar, means for supporting the same, a scraper indirectly supported by said bar, a rod 117 connecting said bar to a crank which is fixed upon a shaft 115, a shaft 109 operatively connected to shaft 115, and a hand-wheel mounted on the shaft 109; substantially as described. 80
13. In a wheeled grader, a frame, a pair of rock-shafts, mounted thereon provided with arms, a scraper suitably connected to the arms, and means connected to the rock-shafts to assist in vertically adjusting the scraper. 85
14. In a wheeled grader, a frame, a pair of rock-shafts mounted thereon provided with arms, a scraper suitably connected to the arms, and springs suitably connected to the rock-shafts to assist in vertically adjusting the scraper.
15. In a wheeled grader, a frame, a pair of rock-shafts mounted thereon provided with arms, a scraper suitably connected to the arms, cams rigidly mounted upon the rock-shafts, and tension-springs connected at their opposite ends to the cams and the frame, substantially as shown. 90
16. In a wheeled grader, a frame, a pair of rock-shafts mounted thereon provided with arms, a scraper suitably connected to the arms, cams rigidly mounted upon the rock-shafts, tension-springs connected at their opposite ends to the cams and the frame, substantially as shown, worm-gearing for operating the rock-shafts, and independently 95

mounted hand-wheels for operating the worm-gearing.

17. In a wheeled grader, a scraper suitably supported, a horizontally-disposed gear-wheel suitably connected to the scraper, a sway-bar suitably connected to the scraper for imparting longitudinal movement thereto, a shaft carrying a worm meshing with the gear-wheel, a sleeve connected to the worm-shaft by a universal joint, an intermediate

shaft slidingly connected to the sleeve and which rotates the latter, and an operating-shaft connected to the intermediate shaft by means of a universal joint.

In testimony whereof I affix my signature ¹⁵ in the presence of two witnesses.
